(57) **CLAIM**

The ornamental design for a paperboard deodorant container, as shown and described.

DESCRIPTION

FIG. 1 is a perspective view of a paperboard deodorant container, showing my new design;

FIG. 2 is a front elevation view thereof, the rear elevation view being a mirror image thereof;

FIG. 3 is a top plan view thereof;

FIG. 4 is a bottom plan view thereof;

FIG. 5 is a side elevation view, with the other side elevation view being a mirror image thereof;

FIG. 6 is a sectional view thereof, taken along line 6-6 of FIG. 3; and,

FIG. 7 is an exploded view thereof.

The broken lines shown in the drawings depict portions of the article that form no part of the claimed design.

1 Claim, 6 Drawing Sheets
